US0D1066119S

(12) **United States Design Patent** (10) **Patent No.:** **US D1,066,119 S**
Thalheimer et al. (45) **Date of Patent:** **** Mar. 11, 2025**

(54) **WINGED VEHICLE, TOY, AND/OR REPLICA MODEL THEREOF**

(71) **Applicant:** **REGENT Craft Inc.**, North Kingstown, RI (US)

(72) **Inventors:** **William Thalheimer**, Waltham, MA (US); **Michael Klinker**, Hollis, MA (US); **William Bryan Baker**, Cohasset, MA (US); **Daniel Cottrell**, Centreville, VA (US); **John Andrew Gaynor**, Barrington, RI (US); **Bradley C. Buskirk**, Charlotte, NC (US); **Brett C. Peters**, Warwick, RI (US); **Cory Asher Kays**, Ft. Thomas, KY (US); **Jason Castriota**, Stamford, CT (US); **Marco Borge**, Vopiano (IT); **Edward Lester**, Somerville, MA (US)

(73) **Assignee:** **REGENT Craft Inc.**, North Kingstown, RI (US)

(**) **Term:** **15 Years**

(21) **Appl. No.:** **29/874,061**

(22) **Filed:** **Apr. 13, 2023**

Related U.S. Application Data

(63) Continuation of application No. 17/845,480, filed on Jun. 21, 2022, which is a continuation-in-part of application No. 17/570,090, filed on Jan. 6, 2022, now Pat. No. 11,420,738.
